UNITED STATES PATENT OFFICE.

BERNHARD METZ, OF NEW YORK, N. Y.

DESIGN FOR WATER-PROOF GOODS.

Specification forming part of Design No. 5,432, dated December 19, 1871.

Specification describing a Design for Borders in Repellent or Water-proof Goods, invented by BERNHARD METZ, of New York city, State of New York.

The nature of my design is fully represented in the accompanying drawing, to which reference is made.

A represents a portion of the body of the repellent or water-proof goods, and B a portion of the border. The border consists of fifteen parallel stripes, the middle one the widest. Along the middle stripe *a* of the border run undulating lines, which define two different colors, *c* and *d*. Along the next wider stripes *e e* run undulating lines, these stripes having but one color. The stripes *f f* are ornamented with undulating lines crossing each other, and containing stars *g g*. The following stripes *h h* are again ornamented with an undulating line, which is ornamented with points *i i*.

I prefer to make the colors of the middle stripe red and blue—thus, *c* red and *d* blue, and the undulating lines white; the stripes *e e* green, and undulating lines therein yellow; the stripes *f f* red, and the stars *g g* white, the undulating lines blue; the stripes *h h* green, and the undulating lines yellow; the points black. The other stripes all black; but I do not consider the colors selected to be an essential element in my design.

I claim as my invention—

A design for a border for repellent or water-proof goods, in which the border is placed and ornamented substantially in the manner above shown and described.

BERNHARD METZ.
